ELECTRIC INITIATOR

Carlton M. Slough, Henrico County, Va., assignor to Texaco Experiment Incorporated, Richmond, Va., a corporation of Virginia
Continuation of application Ser. No. 110,012, May 15, 1961. This application May 11, 1964, Ser. No. 366,238
5 Claims. (Cl. 102—70.2)

This application is a continuation of applicant's co-pending application Serial No. 110,012, filed May 15, 1961, for "Electric Initiator," and now abandoned, and assigned to the same assignee as the present invention.

This invention relates to improvements in electric firing initiating devices and, more particularly, to electric initiators which are highly resistant to premature firing by electromagnetic wave energy in the radio frequency range.

The invention relates to electrical firing initiating devices which generally include a shell or casing in which is disposed an electrical resistance element or fuse wire which resistance element or fuse wire is in contact with a heat sensitive ignition composition or match head which, in turn, is embedded in or located adjacent to an explosive charge.

Electrical firing initiating devices are commonly employed to initiate various explosive compositions used as the primary igniter for reaction propelled motors of the liquid or solid propellant types. In general, such electric initiators are designed to be actuated by direct current and the art has long recognized the danger inherent in accidental discharge of such electric initiators by accidentally induced radio frequency electromagnetic wave energy. More recently, this problem of accidental discharge of electric initiators has become more acute since radio frequency guiding systems and control means have been employed in reaction propelled space vehicles along with electrical firing initiating devices.

It is, therefore, a primary object of the present invention to provide a direct current actuated electric initiator safeguarded against premature or accidental initiation by radio frequency electromagnetic wave energy induced therein.

A further object is to provide improved radio frequency electromagnetic wave energy protected electric initiator without substantially reducing the degree of sensitivity of the electric initiator to actuation by direct current.

A further object is to provide such an initiator which is relatively simple in construction and relatively inexpensive to manufacture.

In general, the invention consists of an electric initiator safeguarded against premature initiation by radio frequency electromagnetic wave energy comprising a fuse wire, a heat sensitive ignition composition in heat exchange relationship to the fuse wire, an electrical conductor having one end connected to one end of the fuse wire and the other end of the electrical conductor being connectable to a source of initiating current, an electrical conductive tubular member surrounding the electrical conductor for an appreciable length in the direction toward the initiating current source, and electrically and mechanically encasing the fuse wire and ignition composition and connected to the other end of the fuse wire, said tubular member being dimensioned to be non-transmitting of electromagnetic wave energy of frequencies up to at least about 2 kilomegacycles.

The invention will be more particularly described with reference to the illustrative embodiments thereof shown in the accompanying drawings wherein:

FIG. 1 is a sectional view of an electrical initiator embodying the principles of the present invention;

FIG. 2 is an enlarged transverse section substantially on line 2—2 of FIG. 1;

FIG. 3 is an enlarged horizontal sectional view similar to that shown in FIG. 2 of a modified form of the present invention wherein the outer electrical conductive member is rectangular in plan; and

5 FIG. 4 is an enlarged horizontal sectional view similar to that shown in FIG. 2 of a modified form of the present invention wherein the inner conductor is provided with an electrical insulating jacket and the jacket is positioned against one wall of the outer electrical conductive member or conduit.

10 Referring to the drawings, 10 generally designates the improved electric initiator safeguarded against premature initiation by radio frequency electromagnetic wave energy induced therein. The initiator includes an electrical resistance heater element or conventional fuse wire 12. The fuse wire 12 is in contact or in heat exchange relationship to a heat sensitive initiator composition 14. Further, as illustrated in the drawings, a primer spot or match head 16 may be in contacting relationship to the fuse wire 12 and provide the initial ignition composition. A suitable primer spot may comprise, for example, mercury fulminate or lead azide.

15 End 12' of the fuse wire 12 is electrically connected to one end of an electrical conductor 18 which is illustrated in the drawings as a cylindrical copper wire. The remote end 18' of the electrical conductor 18 is adapted to be connected to a source of initiating current, not shown, which, as will be more fully appreciated hereinafter, is direct current or very low frequency alternating current.

20 The conductor 18, the fuse wire 12 and the ignition composition 14 are provided with a tubular electrical conductive housing generally designated 20. The illustrated housing 20 includes a conductive tubular conduit 22 having a substantially greater diameter than the conductor 18 and the conductor 18 in this form of the invention is maintained in substantially equidistant spaced relationship from the inner wall 24 by one or more electrical insulating spacers 26. The length of the tubular conduit 25 22 of the conductive tubular member 20 is critical for the distance illustrated in FIG. 1 wherein it surrounds conductor 18, as further described below.

25 A conventional coaxial nut connector 28 is illustrated at the upper end of conduit 22. It is rotatable on the conduit and in electrical contact therewith. The remote end 18' of the conductor may be terminated in any of the standard coaxial fittings, i.e., pin, socket, button-contact, etc., not shown, which are well known in the art. The choice of a particular termination will be dictated by 30 the type of electrical connections extending from connector nut 28 to the source of initiating current. The length and type of such connections extending from nut 28 are not critical, and open wire, coaxial cable, printed circuits, or the like, may be used.

35 55 Nut 28 provides a return connection path for the initiating current which is carried to the other end of the fuse wire by means of the conductive housing 20 as described below. Thus, when connected in circuit, the entire initiator assembly 10 will be grounded, as schematically indicated, to shield the same against the entry of radio frequency electromagnetic wave energy at all points other than 18', 28.

60 The electrical conductive tubular member 22 may be circular or polygonal in cross-section with an inside diameter or side dimensioned to be non-transmitting of electromagnetic wave energy of frequencies up to at least about 2 kilomegacycles to insure adequate protection for the initiator.

65 70 Premature initiation by radio frequency electromagnetic wave energy has been found to occur when the raceway or the conduit carrying the fuse wire conductors acts as a waveguide. Where such a raceway or conduit is

discontinuous at any point, an entrance is provided for radio frequency wave energy and the conduit acts as a waveguide such that the energy is propagated down the waveguide to the fuse wire. At certain frequencies, depending upon the length and cross-sectional dimensions of the conduit attached to the initiator and the physical size of the initiator case, the initiator case acts as a resonant cavity and the fuse wire a pickup probe. Heating of the fuse wire and initiation of the igniter composition can, therefore, occur if sufficient electromagnetic wave energy is present.

By proper selection of the dimensions of the tubular member 22, the conductive tubing can be made non-transmitting of electromagnetic wave energy below a predetermined frequency. Thus any radio frequency induced energy present on the fuse wire conductors leading up to connector nut 28 will be attenuated in accordance with the invention to prevent the accidental actuation of fuse 12. For example, a quadrangular waveguide 10 mm. along its greatest side has a cut-off frequency of 15 kilo-megacycles; that is, below 15 kilo-megacycles, the conductive tube will not propagate a wave. For a circular waveguide having the same cut-off frequency, its inside diameter is 1.17 times the permissible inside dimensions of a polygonal conduit providing a permissible diameter of 11.7 mm. for a cut-off frequency of 15 kilo-megacycles.

The cut-off frequency for a given waveguide below which it will not propagate a wave is determined by the formula

$$F_{co} = \frac{C}{2a}$$

where F_{co} is the lower cut-off frequency; a is equal to the major waveguide interior cross-section dimension in centimeters; and C is equal to 3 times 10^{10} cm. per second, or the velocity of light. The free-space wavelength λ_{co} corresponding to F_{co} is related thereto by the formula $C = \lambda F$, and therefore dimension a will be equal to $\frac{1}{2}\lambda_{co}$ measured in centimeters.

A waveguide is a rather narrow band transmission system which produces a rapid attenuation of electromagnetic wave energies that are below the cut-off frequency. Energies are usually negligible at distances along the waveguide of a length slightly in excess of the major transverse interior dimension of $a = \frac{1}{2}\lambda_{co}$. In order to provide an increased safety factor in accordance with the invention, however, a minimum length for tubular member 22 should be not less than two wavelengths. Thus, in the preceding examples for a cut-off frequency of 15 kilo-megacycles, the 10 mm. wide quadrangular waveguide should have a minimum length of 40 mm.; and the circular waveguide, 46.8 mm.

The lower end of the tubular member 22 may house the fuse wire 12 and the ignition composition 14; however, where the inside diameter of the tubular member 22 is not sufficiently large to contain sufficient ignition composition, the lower end 28 of the tubular member 22 receives a further electrical conductive housing portion 30. The housing portion 30, which may be tubular, is provided with an electrical conductive wall or roof 32 having a central opening therein which is connected to the lower end 28 of the conductor 22. The tubular conductor 22 and the wall portion 32 of conductor 30 are welded, sweated or otherwise secured together so that radio frequency electromagnetic wave energy cannot leak into the system at the joint.

End 34 of fuse wire 12 is electrically connected to the inner wall 36 of the conductive member 30 by an electrical conductor 38. Further, the lower end of member 36 is closed by an electrical energy shield 40 preferably comprising a thin metal foil which is either burnable or rupturable upon ignition of the igniter composition 14. The foil is suitably soldered as at 42 to the wall of the conductor 30 to prevent leakage of RF energy

into the housing containing the fuse wire 12. Similarly, an initiation destructible electrical shielding foil 44 is provided adjacent the upper surface of the initiator composition to contain such composition. The extremities 5 of the foil 44 are suitably electrically connected to the inner wall of the conductive housing 30 with the joint therebetween suitably formed to prevent the entry of radio frequency energy into the initiator proper. Further, as illustrated in the drawings, foil 44 is insulated 10 from the conductor 18 as at 45.

A further protection for the initiator against premature initiation by radio frequency electromagnetic wave energy may be provided by the proper choice of the diameter of the conductor 18 in relationship to the inside diameter of the tubular conductive member 22 whereby the impedance of the system, when considered as a coaxial cable, may be varied through a range of, for example, 42 to 150 ohms without lowering the cut-off frequency of the tubular member 22. This provides a 15 choice of mismatch conditions between the coaxial line and the fuse wire which further reduces the possibility of ignition of the igniter composition 14 from radio frequency electromagnetic energy which might be induced 20 on the center conductor 18.

25 The impedance of a coaxial line (Z_0) is:

$$Z_0 = 138 \log_{10} \frac{d_1}{d_2}$$

where d_1 is the inside diameter of the outer conductor 30 (conduit 22 or the greater dimension of the rectangular conduit 22' of the drawings) and d_2 is the outside diameter of the inner conductor (member 18 of the drawings).

With a copper tube 22 having an inside diameter of 11.7 mm. as the outer conductor and varying the size of 35 the inner conductor with the firing current capacity as a limit, a substantial range of mismatch impedance can be obtained as indicated in the following chart:

40	AWG Wire Size	Diameter, mm.	Current Capacity, Amps.	Z_0 , Ohms
18.....		1.0	3.0	147
14.....		1.6	15.0	120

45 With the conditions indicated above, if the fuse wire 12 has an impedance of 1.0 ohm, then a mismatch ratio of 147 and 120, respectively, is provided with a copper wire conductor 18 having an AWG wire size of 18 and 50 14, respectively, in combination with a copper outer tube 55 having an inside diameter of 11.7 mm. Such mismatch conditions result in both a lower power transfer and a lower efficiency of energy transfer providing better protection against accidental initiation of the ignition composition due to accidental radio frequency pickup on the electrical conductive conduits. When it is required to 60 initiate the electrical igniter direct current is employed; therefore, the impedance of the coaxial line system has substantially no effect as the impedance is simply the direct current resistance of the fuse wire 12 in series with the direct current resistance of the center electrical conductor 18.

Where the outer tubular conductive conduit 22 and the inner conductor 18 are constructed of conductive materials other than copper, greater or lesser losses may be introduced depending on the conductivity of the material used.

65 FIG. 3 is an enlarged horizontal sectional view, similar to that shown in FIG. 2, of a form of the present invention wherein the outer electrical conductive conduit 22' is rectangular in plan and dimension d_1 is 10 mm. The inner conductive member 18 of the illustrated device has a diameter d_2 of 1.0 mm.

70 Referring to FIG. 4 of the drawings, there is shown a further form of the present invention wherein the outer conductive member is illustrated as a cylindrical conduit 22" and the inner conductor 50 is provided with an elec-

trical insulative coating or jacket 52 and the insulated conductor assembly is positioned against the inner wall of the conduit 22". This form of construction is particularly advantageous where long runs and/or sharp bends are required in the system which would affect the position of the center conductor in the forms of the invention shown in FIGS. 1 through 3.

It is particularly pointed out that the cut-off frequency is of prime importance and the form of the invention illustrated in FIG. 4 exhibits substantially no loss of effectiveness as a protective device for electric initiators even though this form of the device does not have the added protection provided by mismatch conditions which can be built into the systems shown in FIGS. 1 through 3.

From the foregoing description, it will be readily appreciated by those skilled in the art that the present invention fully accomplished the aims and objects hereinabove set forth and that various modifications may be made in the disclosed forms of the invention without departing from the scope of the appended claims. For example, while the illustrated examples of the invention disclose devices having cut-off frequencies of about 15 kilo-megacycles, the principles of the invention may be utilized in devices having substantially higher or lower cut-off frequencies. As hereinbefore set forth, according to the formula

$$F_{co} = \frac{C}{2a}$$

the smaller the outer conductive tube, the higher the cut-off frequency, and substantially the only limitations which would be imposed would be the ability to make initiators of small physical size and the necessity that the center conductor must have a firing current carrying capacity. At the other end of the range, it has been found to be desirable that the outer tubular member be dimensioned to be non-transmitting of at least the standard broadcast frequency electromagnetic wave energy. Therefore, the outer tubular member should be dimensioned to be non-transmitting of electromagnetic wave energy of frequencies up to at least about 2 kilo-megacycles and, preferably, up to at least 10 kilo-megacycles.

I claim:

1. An electric initiator safeguarded against premature initiation from radio frequency electromagnetic wave energy comprising a fuse wire, a heat sensitive composition in heat exchange relationship to the fuse wire, an electrical conductor having one end connected to one end of the fuse wire and the other end of the electrical conductor being connectable to a source of initiating current, an electrically conductive tubular member surrounding the electrical conductor and extending from a point adjacent said one end of the fuse wire a length equal to the length of the electrical conductor, said length being not less than two wavelengths, λ_{co} , at a cut-off frequency of F_{co} , said tubular member being dimensioned transversely such that F_{co} equals $C/2a$ where a is equal to the major waveguide interior cross-section dimension in centimeters, C is equal to the velocity of light in centimeters per second and F_{co} is equal to at least about 2 kilo-megacycles; conductive electrical shielding means encasing said fuse wire and said heat sensitive composition, said shielding means having one wall surface mechanically and electrically joined to said tubular member, and at least one further wall surface formed of initiation destructible conductive material, and electrical conductor means electrically connecting the other end of the

and electrical conductor means electrically connecting the other end of the fuse wire and said shielding means.

2. An electric initiator safeguarded against premature initiation from radio frequency electromagnetic wave energy comprising a fuse wire, a heat sensitive ignition composition in heat exchange relationship to the fuse wire, an electrical conductor having one end connected to one end of the fuse wire and the other end of the electrical conductor being connectable to a source of initiating current, an electrically conductive tubular member surrounding the electrical conductor and extending from a point adjacent said one end of the fuse wire a length equal to the length of the electrical conductor, said length being not less than two wavelengths, λ_{co} , at a cut-off frequency of F_{co} , said conductive tubular member being circular in plan and dimensioned transversely such that F_{co} equals $C/2a$ where a is equal to the waveguide interior diameter in centimeters, C is equal to the velocity of light in centimeters per second and F_{co} is equal to at least about 2 kilo-megacycles; conductive electrical shielding means encasing said fuse wire and said heat sensitive composition, said shielding means having one wall surface mechanically and electrically joined to said tubular member, and at least one further wall surface formed of initiation destructible conductive material, and electrical conductor means electrically connecting the other end of the fuse wire and said shielding means.

3. The invention defined in claim 2 wherein the impedance of the electrical conductor and said tubular member is greater than the impedance of the fuse wire.

4. The invention defined in claim 3 wherein the tubular member has an inside diameter of 11.7 mm. and the said electrical conductor has a diameter of from about 1 to about 1.6 mm.

5. An electric initiator safeguarded against premature initiation from radio frequency electromagnetic wave energy comprising a fuse wire, a heat sensitive composition in heat exchange relationship to the fuse wire, an electrical conductor having one end connected to one end of the fuse wire and the other end of the electrical conductor being connectable to a source of initiating current, an electrically conductive tubular member surrounding the electrical conductor and extending from a point adjacent said one end of the fuse wire a length equal to the length of the electrical conductor, said length being not less than two wavelengths, λ_{co} , at a cut-off frequency of F_{co} , said tubular member being rectangular in cross-section and dimensioned transversely such that F_{co} equals $C/2a$ where a is equal to the major waveguide interior cross-section dimension in centimeters, C is equal to the velocity of light in centimeters per second and F_{co} is equal to at least about 2 kilo-megacycles; conductive electrical shielding means encasing said fuse wire and said heat sensitive composition, said shielding means having one wall surface mechanically and electrically joined to said tubular member, and at least one further wall surface formed of initiation destructible conductive material, and electrical conductor means electrically connecting the other end of the fuse wire and said shielding means.
